US00D888946S

(12) **United States Design Patent** (10) **Patent No.:** **US D888,946 S**
(45) **Date of Patent:** **** Jun. 30, 2020**

(54) **MEDICAL DEVICE HANDLE**

(71) Applicant: **ABBOTT CARDIOVASCULAR SYSTEMS INC.**, Santa Clara, CA (US)
(72) Inventors: **Michael L. Green**, Pleasanton, CA (US); **Matthew J. Gillick**, Murrieta, CA (US); **Eugene Canavan**, Wicklow (IE)

(73) Assignee: **Abbott Cardiovascular Systems Inc.**, Santa Clara, CA (US)

(**) Term: **15 Years**

(21) Appl. No.: **29/628,958**

(22) Filed: **Dec. 8, 2017**

Related U.S. Application Data

(63) Continuation of application No. 14/932,862, filed on Nov. 4, 2015, now Pat. No. 10,271,980, and a continuation of application No. 14/932,805, filed on Nov. 4, 2015, now abandoned, and a continuation of application No. 14/932,795, filed on Nov. 4, 2015, now abandoned, and a continuation of application No. 14/932,848, filed on Nov. 4, 2015, now Pat. No. 10,149,778, and a continuation of application No. 14/932,884, filed on Nov. 4, 2015, now Pat. No. 10,195,065, and a continuation of application No. 14/932,900, filed on Nov. 4, 2015, now Pat. No. 10,154,920, and a continuation of application No. 14/932,830, filed on Nov. 4, 2015, now Pat. No. 10,433,994.

CLAIM

The ornamental design for a medical device handle, as shown and described.

DESCRIPTION

FIG. 1 is a right perspective view as viewed from a front, which is a mirror of the opposing side, of a medical device handle;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines shown throughout these figures depict environmental subject matter only and form no part of the claimed design.

1 Claim, 7 Drawing Sheets
